GAS AND NOXIOUS POWDER GUN

Joseph Williams, Jr., Pittsburgh, Pa., assignor to
Chemical Protective Arms Corporation, a cor-
poration of Pennsylvania

Application March 8, 1934, Serial No. 714,613

4 Claims. (Cl. 42—2)

The invention relates to a gun for the projection of either a volume of gas or a noxious or irritating character, which is generated in the gun incident to the heat of discharge, or for the projection of a body of finely divided powder of noxious or irritating character, such as diphenylaminechlorarsine, which does not form a gas, but has somewhat similar effects. The invention has for its objects the provision of an improved gun adapted to employ either the foraminous type of cartridge, which carries a gas generating powder, or the type of cartridge having imperforate side walls and which discharges a noxious powder through its end. Heretofore a different gun has been required for each type of cartridge. A further object is the provision of a gun having improved means for centering both types of cartridges, so that they are properly centered in the barrel of the gun without difficulty or loss of time. A further object is the provision of a gun of the character specified, of simple durable construction, which has a relatively flexible body portion adapting it specially for police work. Certain embodiments of the invention are shown in the accompanying drawing, wherein:

Figure 1 is a side elevation of the device. Fig. 2 is a longitudinal section. Fig. 3 is a face view of the cartridge centering plate located in the barrel. And Fig. 4 is a fragmentary sectional view showing a slight modification.

Referring to the drawing, 1 is the grip or handle of the gun which carries the firing plunger 2, and 3 is the barrel which is screwed into the end of the grip. The plunger is provided with a firing pin 4, and is moved forward to fire the cartridge 5 by means of the spring 6. The plunger is retracted by means of the thumb piece 7 mounted on the grip for sliding movement longitudinally thereof. The plunger is provided with a pin 8 which extends through a slot in the wall of the grip and engages a shoulder at the end of a slot on the lower side of the thumb piece, so that when the thumb piece is moved to the right to the position of Fig. 2, the plunger is carried with it. The plunger is locked in retracted position by means of a ball 9 carried in a slot in the plunger and pressed upward by the spring 10. A release ball 11 is carried in a socket on the lower side of the thumb piece, and when the thumb piece is moved to the left, the ball 11 engages the ball 9 and presses it down, thus releasing the plunger. This firing mechanism is shown and described in greater detail in my copending application of even date, Serial No. 714,612, and no claim is made thereto in the

present application. It will be understood that any suitable firing means may be substituted. A breech block 12 is screwed into the end of the grip or handle in advance of the plunger.

The frame of the device consists of a heavy coil spring 13 which is attached securely to the barrel by screwing it thereon, the barrel being suitably threaded for this purpose. The spring is similarly attached at its outer end to the nozzle piece 14. The frame is cushioned or padded by a sheath 15 of rubber, which is relatively soft and which is secured to the spring 13 and member 14 either by molding it in position or by screwing it thereover.

Insertable into the barrel from the rear end 15 when the barrel is unscrewed, is the cartridge 5, which is of the gas generating type having its side wall perforated and its front end closed by a cap 16. The rear end 17 of the cartridge, which carries the charge of explosive powder, fits 20 snugly into the reduced rear end portion of the barrel, thus centering the cartridge at its rear end. The space 18, which is provided between the wall of the cartridge and the wall of the barrel, permits a free outflow of the gas generated 25 through the wall of the cartridge. Anchored at the front end of the barrel is a supporting and centering plate 19. This plate carries a centering cup 20, into which the cap 16 on the cartridge fits, and is provided around this cup with 30 the perforations 21 which permit the gas discharged into the space 18 to flow forward through the gun and discharge through the nozzle 14. The plate also has an opening 22 at its center, so that when a noxious powder cartridge is used having imperforate sides and an open end, the discharge can occur through this control opening. The gun can thus be used either with a gas generating cartridge having perforated or foraminous walls and an end closure, or 35 with a cartridge which discharges a noxious powder and thus requires an open end. In both cases, the plate 19 permits of a free discharge, and at the same time, acts to center the outer end of the cartridge.

In order to sheath the spring frame 13 which would otherwise be exposed to the gases of combustion between the plate 19 and the nozzle 14, the tube 23 is provided, such tube being of flexible construction and formed by the use of a flexible metal strip. A smooth bore is thus provided which is readily cleaned, and the spring 13 is protected from the action of the gases of combustion. Because of its flexible character, 55

the tube 23 does not materially impair the flexibility of the outer portion of the billy.

Fig. 4 illustrates a somewhat different means for anchoring the centering plate 19 with respect to the end of the barrel. In this construction, the plate 19 fits tightly in the end of the barrel with the extreme end of the barrel peened over, as indicated at 24.

What I claim is:

- 10 1. In combination in a gas gun, a grip or handle, a barrel secured releasably at its rear end to the grip, said barrel having a reduced diameter at the rear end of its bore adapted to fit the cartridge used in the gun and to center it, and having a larger diameter from such reduced diameter outward, and a cup member anchored with respect to the barrel for centering and supporting the forward end of the cartridge, said member having outlet means adjacent its periphery to permit a flow of gas past it.
- 15 2. In combination in a gas gun, a grip or handle, a barrel secured releasably at its rear end to the grip, said barrel having a reduced diameter at the rear end of its bore adapted to fit the cartridge used in the gun and to center it, and having a larger diameter from such reduced diameter outward, and a plate provided at its center with a cup anchored in the barrel and adapted to engage and center the forward end of the cartridge, such cup being open at its center, and the plate surrounding the cup being perforated.

3. In combination in a gas gun, a grip or handle, a barrel secured releasably at its rear end to the grip, said barrel having a reduced diameter at the rear end of its bore adapted to fit the cartridge used in the gun and to center it, and having a larger diameter from such reduced diameter outward, means anchored at the end of the barrel for engaging and supporting the forward end of the cartridge, a coil spring frame secured at its rear end to the barrel, a yielding cushion over the barrel and frame, and a flexible metallic tube yieldingly held in the frame in advance of the means anchored at the end of the barrel and constituting a sheath for the spring frame.

4. In combination in a gas gun, a grip or handle, a barrel secured releasably at its rear end to the grip, said barrel having a reduced diameter at the rear end of its bore adapted to fit the cartridge used in the gun and to center it, and having a larger diameter from such reduced diameter outward, means anchored at the end of the barrel for engaging and supporting the forward end of the cartridge, a coil spring frame secured at its rear end to the barrel, a metal nozzle secured to the outer end of the spring frame, a yielding cushion over the barrel, frame and nozzle, and a flexible metallic tube fitting in the spring frame and extending forward from the means anchored at the end of the barrel to the nozzle.

JOSEPH WILLIAMS, JR.
